UNITED STATES PATENT OFFICE.

HENRY E. WEBER, OF CANTON, OHIO, ASSIGNOR TO THE WEBER DENTAL MANUFACTURING COMPANY, OF CANTON, OHIO, A CORPORATION OF OHIO.

RESERVOIR-CUSPIDOR.

1,111,047.

Specification of Letters Patent. Patented Sept. 22, 1914.

Application filed August 30, 1910. Serial No. 579,696.

To all whom it may concern:

Be it known that I, HENRY E. WEBER, a citizen of the United States, residing at Canton, in the county of Stark and State of Ohio, have invented a certain new and useful Reservoir-Cuspidor, of which the following is a specification.

The invention relates to a reservoir cuspidor for use in places where connections with water supply and sewer systems are not available or desirable; and the object of the improvement is to provide a complete, convenient and sanitary cuspidor which will present a neat and clean appearance. The adhesion of sanguinary saliva to the bottom of a cuspidor cannot be overcome by an intermittent flushing of the same, and, when such flushing is depended upon to remove the saliva, a certain portion of the same with its disease-breeding germs will accumulate and ultimately dry in the cuspidor, which renders it unsightly as well as unhealthy. This difficulty is overcome by normally flooding the bottom of the bowl, so that the saliva will not impinge the same, and by frequently draining off the flooding water and replacing it with a fresh and clean supply.

The invention also includes other improvements of construction, arrangement and operation, which are illustrated in the accompanying drawings, forming part hereof, showing a preferred embodiment of the invention, in which—

Figure 1 is a side elevation of the reservoir cuspidor; Fig. 2, a sectional elevation of the same; Fig. 3, an enlarged fragmentary section of the pump valves and adjacent parts; Fig. 4, an enlarged fragmentary section of the bowl support and outlet valve, also showing the pump handle and flushing nozzle; Fig. 5, a fragmentary perspective view showing details of the bowl-bracket stopping device; and Fig. 6, a perspective view of the cuspidor showing an alternate manner of supporting the waste bucket, and showing the bowl and bucket brackets rotated from above the reservoir, and the bucket removed from its bracket.

Similar numerals refer to similar parts throughout the drawings.

The reservoir cuspidor is composed of the reservoir 1, on which is formed or connected the base 2; the tubular stem 3, which forms the pump cylinder and is secured to

the socket 4 formed on one side of the base, by means of the nipple 5 and the union coupling 6, and to the reservoir by the connecting arm 7; the waste bucket 8 or 8^a, which is supported at the top of the reservoir, either by resting directly thereon, as shown in Figs. 1 and 2, or by resting in the bracket 9 which is rotatably supported on the tubular stem 3, as shown in Fig. 5; and the bowl 10, which is supported at the top of the bucket by means of the bracket 11 rotatably supported on the tubular stem.

The reservoir 1 is preferably made, as shown, in the form of a round vessel open at the top and provided with the enlarged base 2 on the bottom, which constitutes a firm support for the cuspidor. The socket 4 is formed or secured on one side of the base and communicates with the bottom of the cavity of the reservoir by the port 12. The check valve 13 is provided in the lower end of the tubular stem and the plunger 14 is located and adapted to operate endwise in the tubular stem, which plunger is provided with the handle 15 on its upper end, and is made somewhat less in external diameter than the interior diameter of the tubular stem, thus leaving the intervening annular chamber 16 around the plunger. The stuffing box 17 is provided at the upper end of the cylinder, and the flexible cup-valve 18 is secured to the shank plug 19 on the lower end of the plunger; and the resilient washer 20 is preferably secured to the lower end of the valve-shank and serves to cushion the contact of the plunger against the check valve.

The flushing nozzle 21 is connected by the swivel-union 22 to the tubular branch 23 on the side of the upper end of the tubular stem and communicates with the cavity thereof; which nozzle is suitably bent so that by a rotation of the nozzle on its swivel-union, the discharge end 24 thereof may be brought down to or near the bottom of the bowl, as shown in Fig. 2, or the nozzle may be raised so that the overhanging portion thereof will be elevated entirely above the rim of the bowl, as shown in Fig. 6, or by broken lines in Fig. 2.

In the operation of the pump, when the plunger is raised the edge of the cup-valve is flexed outward and impinges the wall of the cylinder, thus sucking the water from the cylinder through the port 12 and up.

ward through the socket 4 and check valve 13 into the cavity of the tubular stem; and at the same time lifts such water as may be above the cup-valve and discharges it 5 through the nozzle. And, when the plunger is depressed, the check valve 13 is closed by the weight of the column of water above it, and the displacement of the plunger forces the water upward around the same and out 10 ward through the nozzle.

The waste bucket 8 or 8^a is preferably made cylindric in form, as shown, with a holding capacity slightly less than the capacity of the reservoir. When the bucket is 15 supported directly on the rim 25 of the reservoir, as shown in Figs. 1 and 2, the depending flange 26 is preferably provided around the bottom of the bucket, which flange overlaps the rim of the reservoir and 20 centers and retains the bucket in place thereon; and the depending flange furthermore prevents any waste which may overflow from or run down the sides of the bucket, from finding its way into the reservoir.

The bucket bracket 9 is preferably made 25 in the form of a shallow cup, which may have its bottom apertured, as shown, in which cup the bottom of the bucket is readily centered and retained; and the bracket 30 is provided with the arm 27 and the bearing sleeve 28 which is journaled on the tubular stem and supported on the collar 29 of the arm 7^a which secures the stem to the reservoir. The set screw 30 is preferably 35 provided in the bearing sleeve by means of which the bucket bracket may be secured in any desired position of rotation. In use, the bracket 9 is normally located immediately 40 above the top of, and in axial alignment with the reservoir, as shown by broken lines in Fig. 6; but, when it is desired for filling the reservoir, or to remove the bucket without rotating the bowl, the bracket is 45 rotated from above the reservoir, as shown in Fig. 6.

The bowl bracket 11 is preferably made 50 bell-shaped in form with its rim 31 normally located immediately above the rim 32 of the bucket, thus forming an arched cover for the same; and the countersunk bowl-seat 33 is provided on the upper side of the bracket in which seat the neck of the bowl is adapted to be secured, preferably with the intervening resilient washer 34. The discharge ajutage pipe 35 is axially formed, or 55 secured by screwing, as shown, in the bowl bracket, and its lower end 36 depends freely a considerable distance below the body of the bell-shaped bracket, but terminates above 60 the level of the rim thereof. The funnel-shaped partition 37 is provided in the drain pipe, the lower rim 38 of which is located at a substantial annular interval within the wall of the ajutage pipe above the 65 lower end thereof, and constitutes a seat

against which the valve 39 is adapted to be closed; which valve is secured on the inner end of the lever 40 which is fulcrumed at 41 in the hollow arm 42 of the bowl bracket and preferably above the plane of the valve 70 seat. The outer end of the lever 40 is normally depressed to close the valve, as shown in Fig. 2, by means of the spring 43 adjustably mounted in the bracket-arm, and the same end of the lever is adapted to be elevated to open the valve, as shown in Fig. 4, by means of the push pin 44 mounted in the socket 45 in the bracket arm, and provided with the stop collar 46 adapted to engage the guide flange 47 to retain the 80 pin in the socket.

The bowl 10 is preferably secured in its seat in the bracket 11 by means of the funnel-shaped collar 48, the neck of which is connected, as by screwing, with the upper 85 end of the drain pipe 35, and the flared end of which collar is adapted to impinge around the bottom of the bowl above its neck, preferably with the intervening resilient packing ring 49, thereby clamping 90 the neck of the bowl in its bracket-seat.

The bearing sleeve 50 is provided on the end of the bowl-bracket arm 42 which bearing is journaled on the tubular stem 3, and its lower end rests on the supporting collar 95 51 which is secured to the stem. The annular recess 52 is provided in the lower end of the bowl-bracket sleeve 50 part way around the same, in which recess the stop pin 53, formed or secured on the supporting 100 collar 51, projects and serves to limit the rotation of the sleeve in either direction by impinging the respective ends of the annular recess therein. These parts are so proportioned and arranged that the lateral 105 swinging of the bowl-bracket in one direction is stopped when the bowl is in axial alignment directly above the reservoir and the bucket, as shown in Figs. 1 and 2, and its lateral swinging in the opposite direction 110 is stopped when the bowl and its bracket have cleared the side of the bucket, as shown in Fig. 6. The set screw 54 is preferably provided in the bowl-bracket sleeve by means of which the same can be locked in a 115 desired position of rotation.

In the use of the cuspidor, the reservoir is charged with clean water by means of the waste bucket, which is removed for that purpose either by elevating the discharge nozzle 120 and swinging the bowl to one side, when the bucket 8 is supported on the reservoir; or, if desired, by merely rotating the bucket-bracket when the bucket 8^a is supported independently of the reservoir. The empty 125 bucket is then placed in normal position above the reservoir, and the bowl, if not already there, is swung into normal position directly above the bucket, and the flushing nozzle is depressed to bring its discharge end 130

near the bottom of the bowl. The pump is then operated and one or more strokes of the plunger serves to fill the bowl so that its bottom is entirely covered, as shown in Fig. 2, with fresh and clean water drawn from the reservoir, it being understood that the discharge valve 39 is normally closed by action of the spring 43 thus retaining the water in the bowl. When the cuspidor has been used to such an extent as to render a change of the water therein necessary or desirable, the discharge valve is opened by pressure applied to the free end of the push pin 44, whereupon the water in the bowl flows downward through the ajutage pipe into the bucket, in doing which the freely depending rim of the ajutage pipe serves to prevent any portion of the water from running or splashing against the bell-shaped cover or over the rim of the bucket, thus draining all the water into the bucket. To prevent any water from running outward along the lever of the discharge valve, the same is preferably curved upward from the valve as shown. When the bowl has thus been emptied, the discharge valve is closed and the bowl again filled with fresh water from the reservoir by means of the pump as

before described. After all the water has been pumped from the reservoir and discharged into the bucket, the same is then emptied from the bucket, and, after properly cleansing the bucket, the reservoir is refilled with fresh water as before described. 30

I claim:

1. A cuspidor including a reservoir, a bucket resting upon the rim of the reservoir and having a depending flange overlapping said rim, and a laterally swinging bowl supported above the bucket. 35
2. A cuspidor including a bucket, a bell-shaped bracket independently supported above and normally covering the bucket and a bowl mounted on the bracket. 40
3. A cuspidor including a bucket, a bell shaped bracket independently supported above and normally covering the bucket, and a bowl mounted on the bracket and having a discharge pipe depending freely from the body of the bracket to discharge into the 45 bucket. 50
